Primary Examiner — Cynthia Ramirez*Assistant Examiner* — L. Martinez-Rivera(74) *Attorney, Agent, or Firm* — Leason Ellis LLP(57) **CLAIM**

The ornamental design for an article of jewelry, as shown and described.

DESCRIPTION

FIG. 1 is a front view of an article of jewelry, showing my new design in an environment of use;

FIG. 2 is a side elevational view thereof, the other side views being identical thereto;

FIG. 3 is a front perspective view thereof;

FIG. 4 is another front view of an article of jewelry, shown in an alternative environment of use;

FIG. 5 is a side elevational view of FIG. 4, the other side elevational views being identical thereto; and,

FIG. 6 is another front perspective view of FIG. 4.

The broken lines in the drawings represent environmental subject matter only and form no part of the claimed design.
